UNITED STATES PATENT OFFICE.

RUSSELL H. PECK, OF PALMERTON, PENNSYLVANIA.

BATTER-BOARD.

1,130,926.

Specification of Letters Patent.

Patented Mar. 9, 1915.

Application filed July 7, 1914. Serial No. 849,484.

To all whom it may concern:

Be it known that I, RUSSELL H. PECK, a citizen of the United States, residing at Palmerton, county of Carbon, State of Pennsylvania, have invented certain new and useful Improvements in Batter-Boards, of which the following is a specification.

This invention relates to batter boards and particularly to a clamp for adjustably setting up the batter board to any height or span relative to an excavation. Heretofore such batters as have been in use have consisted simply of a board nailed to the guide posts. The disadvantage of that construction lay in the fact that the batter board could not be adjusted and could not therefore be used again so that the material became waste stock after its initial use. To the end therefore of providing a batter board which will be adjustable both as to height and to span to adapt it to any level I have devised my present invention. In it, I adjustably clamp the board flatwise near each end to the guide posts so that the board may be adjusted both vertically and horizontally.

The construction and operation of my invention will be more fully disclosed in the specification that follows.

In the drawings forming a part of that specification I have shown as an illustrative embodiment a form of batter board and clamp which have been found satisfactory and efficient in use.

Throughout specification and drawings like reference numerals are correspondingly applied, and in these drawings Figure 1 is a view showing one application of my batter board. Fig. 2 is a section of one of the clamps and tightening levers therefor taken on the line 2—2 of Fig. 1, Fig. 3 is a section on the line 3—3, Fig. 2, and Figs. 4 and 5 are details of the removable handle.

In the embodiment selected as an illustration I have shown a batter board 1 in its application to an excavation 2. The batter board is adjustably set up on guide posts 3, driven solid into the ground on each side of the excavation, by clamps of special construction. Each clamp consists of a spring plate 4 to which is riveted or otherwise fastened near each end, the flange 5 of a clamping arm 6. Each arm 6 has its free end formed as a hook 7 adapted to be engaged over the rod 3 in spaced relation to the hook of the coöperating arm of the

clamp. Each pair of arms 6 defines an open ended support in which one end of the batter board is adapted to be inserted and clamped. The clamping is effected by means of a pair of tightening levers 8 removably dovetailed in elliptical cams 9 at their inner ends. Each cam lever is normally disposed so as to bring its cam 9 between one side of the batter board and the spring plate 4. The board is clamped flatwise against the posts by swinging the cam levers 8 until the highest points of their cams 9 engage the board and further movement of the levers is impossible. When this condition is reached the board is firmly clamped at both its ends against the posts and can not be disengaged until the levers are released. The spring plates 4 yield outwardly slightly to permit the cams to turn. The resiliency of the plates is preferably such as to permit the levers to be tightened and released by a partial swing in either direction. This permits the board to be clamped to a new position irrespective of whether or not the levers were returned to their original position before the board was released. In practice I have found that the friction ordinarily developed between the cams and the side of the board is sufficient to hold the levers in tightened position. Obviously, however, a positive lock for the levers when in their tightened position could be very easily provided if desired.

In assembling the batter illustrated, the posts 3 are first driven in the ground one on each side of the trench. The board is then set up on the posts so as to bring its center line string 10 in proper position relative to the pipe 11 and is then firmly clamped by tightening the levers 8. The adjustment of the board for height and for span is had without removing the board from its clamps by releasing the levers and sliding the board and clamps up or down on the posts 3, if an adjustment for height is desired, and by sliding the board transversely in the clamps without moving the clamps, if an adjustment for span is required, until the proper level is established.

While I have shown and described my invention in its application to the field of engineering, it is understood that I do not limit myself to this or any other application but reserve the right to use the invention in any capacity where it would perform the functions intended.

Various modifications in the form and construction of my device may obviously be resorted to within the limits of the appended claims.

5. What I therefore claim and desire to secure by Letters Patent is:—

1. A clamp for adjustably clamping a batter board to its guide post to permit vertical and horizontal adjustment of said board relative to said post, comprising a spring plate vertically disposed and having a pair of spaced clamping arms hooked over said post, and a tightening lever having a cam end engaging said spring plate and spacing said plate from said board for tightening said clamp.

2. A clamp for adjustably clamping a batter board to its guide post to permit vertical and horizontal adjustment of said board relative to said post, comprising a spring plate vertically disposed and having a pair of horizontally disposed spaced clamping arms hooked over said post, and a

cam lever operable by a partial swing in either direction for tightening said clamp. 25

3. In a device for setting grades in combination, a batter board, incompressible guide posts therefor, a pair of clamps adjustably engaging said board and posts, and tightening members engaging said clamps and said board for clamping said board flatly against said posts. 30

4. In a device for setting grades in combination, a batter board, incompressible cylindrical guide posts therefor, a clamp comprising a pair of connected post engaging arms and means for tightening said clamps and engaging the connection for said arms and engaging said board for clamping said board flatly against said posts. 35

40 In testimony whereof I affix my signature in presence of two witnesses.

RUSSELL H. PECK.
